UNITED STATES PATENT OFFICE.

MARIA D'ONOFRIO, OF LORAIN, OHIO.

DESIGN FOR A BEDSPREAD.

40,626.

Specification for Design.

Patented Apr. 12, 1910.

Application filed February 10, 1910. Serial No. 543,193. Term of patent 3½ years.

To all whom it may concern:

Be it known that I, MARIA D'ONOFRIO, a subject of the King of Italy, residing at Lorain, in the county of Lorain and State of Ohio, have invented a new, original, and ornamental Design for a Bedspread, of which the following is a specification, reference being had to the accompanying drawings, forming a part thereof.

The figure is a plan view of one corner of a bed spread, showing my design.

I claim:

The ornamental design for a bed spread, as shown.

MARIA D'ONOFRIO.
